UNITED STATES PATENT OFFICE

1,928,587

TRIMMING MECHANISM FOR SEWING MACHINES

Frederic M. Card, Bridgeport, Conn., assignor to The Singer Manufacturing Company, Elizabeth, N. J., a corporation of New Jersey

Original application May 28, 1930, Serial No. 456,380. Divided and this application July 30, 1931. Serial No. 554,028

6 Claims. (Cl. 112—122)

This invention relates to improvements in trimming mechanisms for sewing machines and more particularly in trimming mechanisms of the type adapted to trim the marginal portions of materials upturned in a presser-foot slot in advance of the point of seam formation.

The primary object of the present invention is to provide for trimming the upturned fabric-margins at a substantially constant distance above the sewing machine work-support in order to insure a more uniform relationship of the trimmed margins in the stitched seam, whether said margins are abutting or slightly overlapping in said seam. This object is accomplished by constructing the trimming mechanism so as to be unresponsive to movements of the sewing machine presser-foot due to slight variations in the thicknesses of the materials, but so as to be capable of yielding to bulky portions of the work, such as cross-seams, and also so designed as to be shifted when the presser-foot is raised for insertion and removal of work.

The foregoing and other objects and advantages in view, together with means whereby the same may be carried into effect, will best be understood from the following description of a preferred embodiment of the invention illustrated in the accompanying drawings, in which:

Fig. 1 is a longitudinal section, partly in front elevation, of a sewing machine containing the present improvement. Fig. 2 is a part front end elevation and part section, of the sewing machine with the upper portion of the bracket-arm omitted. Fig. 3 is a sectional view substantially on the line 3—3 of Fig. 2. Fig. 4 is a view in side elevation, partly in section, of the presser-foot, including a sectional view of the throat-plate and feed-dogs. Fig. 5 is a rear side elevation, partly in section, of the presser-foot and trimming mechanism. Fig. 6 is a top plan view of the presser-foot work-engaging plates, omitting the guard blocks and the auxiliary foot. Fig. 7 is a sectional view of the machine bracket-arm, substantially on the line 7—7 of Fig. 1. Fig. 8 represents perspective views, partly in section, of the presser-foot and the supporting bracket thereof, one of the foot-plates being shown in dotted lines.

This application is a division of my prior patent application Serial No. 456,380, filed May 28, 1930, to which prior application reference may be had for a more complete disclosure of the sewing machine in which the present improvements have been embodied.

Referring to the drawings, the sewing machine

is shown as having a frame comprising a bed-plate 1 from one end of which rises a tubular, supporting base 2 for the standard 3 of a tubular bracket-arm 4, which overhangs the bed-plate 1 and terminates in a head 5. Rising from the bed-plate 1, below the bracket-arm head 5, is a tubular work-supporting post 6 having a hinged closure-plate 7. Suitably secured upon the upper end of the post 6 is a throat-plate 8 provided with a needle-slot 9 and suitable feed-slots for feed-dogs 10 and 11 which may be operated in any appropriate manner to advance the work upon the throat-plate. The throat-plate 8 preferably has a rigid fabric-margin supporting member 12 in front of the needle-slot 9, said member having a crest 13.

Journalized for rotation in suitable bearings provided in the bracket-arm 4 is a main actuating shaft 14, carrying at its outer end a driving pulley 15 and at its opposite end a crank-disk 16. This crank-disk serves to actuate in the usual manner a link 17 operatively connected with a vertically disposed needle-bar 18 journalized for endwise reciprocation in aligned bearing apertures provided in a swinging frame 19. The frame 19 is suspended from a fulcrum-pin 20 to swing about an axis transverse to the axis of rotation of the main-shaft 14, and derives its vibratory movements about the fulcrum-pin 20 from actuating mechanism constructed substantially in accordance with the disclosure in the U. S. patent to C. F. Gray, No. 1,020,089, Mar. 12, 1912. In general, a pitman 21 of which one end is operatively connected with the frame 19 has at its opposite end a split strap 22 embracing an eccentric 23. The eccentric 23 is adjustably secured upon a shaft 24 disposed below and crosswise of the main-shaft 14, which latter has gear connections with the transverse shaft 24 of a character such that said shaft 24 rotates at one-half the speed of rotation of the main-shaft. The needle-bar 18 carries at its lower end a needle 25, which through the described actuating connections therefor is reciprocated endwise and is vibrated laterally to effect the production of zigzag stitches.

Cooperating with the needle 25, below the throat-plate, is a loop-taker 26 which in the present machine is of the rotary-hook type and carries a mass of under thread around which the needle-thread loops are cast in the formation of lock-stitches. The actuating mechanism for the loop-taker 26 may be of any suitable character, that embodied in the present machine being substantially the same as disclosed in my prior Patent No. 1,729,994, Oct. 1, 1929.

100

105

110

Opposed to the feed-dogs 10, 11 is a presser-foot carried by a main presser-bar 27 guided for vertically directed endwise movements in suitable bearings provided in the bracket-arm head 5. 5 This main presser-bar is yieldingly depressed by the usual spring (not shown) and may be raised and lowered by any manually operated means commonly employed for this purpose. Upon the lower end of the presser-bar 27 is secured by a 10 screw 28 a presser-foot supporting bracket 29, having in its front face a rectangular recess 30 with vertically disposed side walls. Snugly fitted in the recess 30 and secured therein by a screw 31 is the vertically disposed, flattened shank 32 of the presser-foot, this construction providing not only for ready removal of the presser-foot 15 from the machine but also for accurately attaching it to the presser-bar. Projecting horizontally forward from the shank 32 are vertically spaced 20 guide-members 33 provided with vertically aligned apertures in which are slidably disposed the vertically directed auxiliary presser-bars 34 and 35. The lower ends of these auxiliary bars carry horizontally disposed shoes 36 and 37 entering the 25 channeled heels 38 and 39 of presser-foot plates 40 and 41, which respectively terminate in upturned toes 42 and 43 and are pivotally mounted upon the shoes 36, 37 by horizontally disposed pivot pins, as 44, passing through the spaced 30 members of the U-shaped heels in a direction crosswise of the line of feed.

The foot-plates 40, 41 are yieldingly depressed independently of each other by springs 45 and 46 coiled about the auxiliary presser-bars 34, 35, said 35 springs being interposed between the upper guide-member 33 of the presser-foot shank and collars 47 and 48 adjustably secured upon the bars 34, 35 to yieldingly rest upon the lower guide-member 33 and thereby limit the downward 40 movement of the foot-plates 40, 41. The collars 46 47, 48 each have a depending guide-fin 49 slidably disposed in a suitable guide-slot in the lower guide-member 33, whereby the bars 34, 35 are 45 confined to vertically directed movements.

The foot-plates 40, 41 are spaced from each other beginning from the toes 42, 43 thereof to 50 form a fabric-margin slot 50 which terminates at a point directly in front of the needle path, at which point the adjacent edges of the foot-plates 55 curve inwardly into abutting relation to together form a split guide-web 51 which serves to deflect under the presser-foot the upwardly directed fabric margins passing through the slot 50. The guide-web 51 which also terminates in front of 55 the needle-path is comparatively narrow in the direction of seam formation, the adjacent edges of the foot-plates rearwardly of said guide-web being cut away to merge into the foot-plate heels 38, 39.

This construction of the foot-plates provides a 60 substantial space between the heels 38, 39 thereof, in which space is disposed an auxiliary or chaining-off foot 52 having its toe spaced rearwardly from the guide-web 51 in the line of seam formation to provide a needle-slot 53 in the presser-foot. The auxiliary foot 52 is preferably rigidly carried by a shouldered guide-bar 54 of which the lower portion is slidably disposed in a vertically directed aperture provided in a guide-block 55 upon the presser-foot shank 32. The reduced upper end of the guide-bar 54 is disposed within a screw-bushing 56 adjustably threaded into the upper side of the guide-block 55, a spring 57 coiled about the reduced portion of the guide-block 55 upon the presser-foot shank 32 and 70 the shoulder of the guide-bar. The foot 52 has an upturned heel 58 which overlies a bent stop-plate 59 secured by a screw 60 upon the rear side of the presser-foot shank 32, whereby downward movement of the foot 52 under the action of the spring 57 is limited. It will be observed that the crest 13 of the fabric-margin supporting member 12 upon the throat-plate rises substantially centrally of the presser-foot slot 50 and that it is 75 in alignment with the auxiliary foot 52.

The machine is provided with a mechanism for trimming the upturned fabric-margins passing through the presser-foot slot 50, said mechanism in the present instance including a horizontally disposed ledger-blade 61 and a horizontally vibratory cutting-blade 62 resting upon the ledger-blade, the cutting edges of said blades meeting in shearing relationship directly above the foot slot 50 and in advance of the guide-web 51. 80

The ledger-blade 61 is rigidly clamped in a split head 63 of a collar suitably secured upon the lower end of a vertically slidable rod 65 journaled in spaced lugs 66 formed on an auxiliary bracket 67 secured by screws as 68, upon a primary 85 bracket 69 fixed by screws, as 70, upon the rear side of the machine head 5. The rod 65 is restrained against oscillation about its longitudinal axis by a forked guide-collar 71 adjustably carried by said rod and embracing a guide-rib 72 on 90 the auxiliary bracket 67. Underlying the collar 71 is a lip 73 projecting laterally from a stop-member 74 secured for vertical adjustment upon the presser-foot supporting bracket 29. The stop-member 74 limits the downward movement of 95 the rod 65, the adjustment being preferably such that the ledger-blade clears the presser-foot plate 40 a sufficient distance to allow for slight rocking movements of said foot-plate 40 about its pivotal support while riding uneven portions of the work. 100 The stop-member 74 also functions to raise the trimmer-blades when the presser-foot is raised for insertion and removal of work. It will be observed that the described construction furthermore provides for adjustably raising and lowering the trimming position with respect to the work-support.

The cutting-blade 62 is rigidly clamped in a holder-collar 75 carried by a rod 76 slidably disposed in vertically aligned apertures provided in 105 spaced lugs 77, projecting forwardly from a rock-arm 78. A spring 79 coiled about the rod 76 is interposed between the upper of the lugs 77 and a forked guide-collar 80 adjustably secured upon the rod above the lower lug 77, whereby the cutting-blade 62 is yieldingly urged into engagement with the ledger-blade 61 which it overlies. The rock-arm 78 has a split hub 81 clamped by a screw 82 upon a sleeve 83 journaled for oscillatory movements upon a vertically disposed fulcrum-pin 84 fixed in vertically spaced bearing-lugs, as 85, upon the primary bracket 69. Projecting laterally from the upper end of the sleeve 83 is an arm 86 connected by an extensible link 87 with an arm 88 depending from one end of a 110 horizontally disposed rock-shaft 89 journaled in a bracket 90 suitably secured to the underside of the machine bracket-arm 4. The other end of the rock-shaft 89 carries a crank-arm 91 pivotally connected with a pitman 92 having a strap 115 embracing an eccentric 93 upon the main shaft 14. It will be observed that the ledger-blade 61 and its supporting means can be removed from the machine independently of the other blade-supporting means by detaching the auxiliary 120

bracket 67 from the machine bracket-arm, and that the entire trimmer-blade supporting mechanism can be removed as a unit from the machine by detaching the primary bracket 69.

5 Secured upon the foot-plates 40, 41, for individual detachment therefrom and disposed adjacent to the fabric-slot 50 therebetween, are guard-blocks 94 and 95 provided in their under faces with recesses 96 and 97 affording the necessary clearance for the trimmer-blades 61, 62, which project through said recesses, to allow the foot-plates 40, 41 to rock slightly about their pivotal supports during the passage of the work without affecting the trimming position. The side face 15 98 of the guard-block 95 adjacent the slot 50 is gradually curved towards its rearward end to extend across said slot 50 and merge with the rearward wall of a slot 99 formed in the guard-block 94, whereby the trimmed-off portion of the work is diverted laterally out of the seam line. Conforming with the diverting-surface curvature of said blocks and disposed directly thereabove in its operative position so as to cooperate with said surface in deflecting the trimmed-off fabric 20 margins, is a diverter-blade 100 having its shank 101 bent to closely embrace the ledger-blade carrying collar. The curved shank 101 of the diverter-blade has a horizontally elongated slot 102 entered by the stop-screw 103 threaded into said collar and passing through a friction washer 104. This construction provides simple supporting means for the diverter-blade, permitting the blade to be readily swung into and out of operative position. Because the function of diverter-blades of this character is well known, the drawings show the blade as swung into its ineffective position to more clearly illustrate the mechanism in part obscured by the blade in its operative position.

25 40 In order to join fabric plies by a butt seam, the marginal portions of such plies upon the work-supporting post are directed upwardly to pass through the presser-foot slot 50, whereupon the shearing elements 61, 62 trim said margins and the trimmed-off surplus is directed laterally out of the path of the needle by the merging diverting surfaces of the guard-blocks 94, 95, aided by the diverter-blade 100. The trimmed-off margins of the plies are then forced downwardly into abutting relation by the presser-foot 45 50 guide-web 51 during the advance of the work by the feeding mechanism.

The abutting fabric plies are joined by a zig-zag-stitch seam formed by the vertically reciprocating and laterally vibrating needle 25 in conjunction with the loop-taker mechanism beneath the throat-plate. The presser-foot plates 40, 41 are each capable of riding uneven portions of the work by reason of their pivotal and bodily yielding support upon the presser-foot body and can readily adapt themselves to differences in thicknesses of the fabric plies being joined. The auxiliary foot 52 rides the seam formed and, as usual, opposes a portion of the feed-dog in the absence of work to assist in chaining-off.

Having thus set forth the nature of the invention, what I claim herein is:—

70 75 1. A sewing machine comprising, in combination, stitch-forming mechanism including a reciprocating needle, a work-support, work-feeding mechanism, a presser-foot yieldingly opposed to the work-support having spaced work-engaging foot-plates between which upturned marginal portions of material are adapted to pass, a trimming mechanism including cooperating shearing

elements disposed to trim said upturned marginal portions of material, means independent of the presser-foot for yieldingly depressing said shearing elements toward the work-support, and a stop-member movable with said presser-foot acting to limit the downward movement of said shearing elements in a position thereof normally clearing the work-engaging foot-plates of the presser-foot.

2. A sewing machine comprising, in combination, stitch-forming mechanism including a reciprocating needle, a work-support, work-feeding mechanism, a presser-bar, a presser-foot carried by said presser-bar having adjacent foot-plates spaced at the forward end thereof to provide between them a slot adapted to receive the upturned marginal portions of material, supporting means for said foot-plates upon the presser-bar providing for yielding movements of the foot-plates independently of each other in a direction away from the work-support, a trimming mechanism including cooperating shearing elements disposed to trim said upturned marginal portions of material, means independent of the presser-foot for yieldingly depressing said shearing elements toward the work-support, and means movable with said presser-bar acting to limit the downward movement of said shearing elements to normally clear said foot-plates.

3. A sewing machine comprising, in combination, stitch-forming mechanism including a reciprocating needle, a work-support, work-feeding mechanism, a presser-foot having adjacent work-engaging foot-plates providing between them a fabric-margin receiving slot in advance of the needle, supporting means for said foot-plates providing for tilting movements of said plates about an axis crosswise of the line of seam and for bodily yielding movements independently of each other in a direction away from the work-support, a trimming mechanism including cooperating shearing elements disposed to trim the upturned marginal portions of the work projecting through said presser-foot slot, means independent of the presser-foot for yieldingly depressing said shearing elements toward the work-support, and means acting to limit the downward movement of said shearing elements to normally clear said foot-plates.

4. A sewing machine comprising, in combination, stitch-forming mechanism including a reciprocating needle, a work-support, work-feeding mechanism, a presser-foot having adjacent foot-plates spaced at the forward end thereof to provide between them a slot adapted to receive the upturned marginal portions of material, supporting means for said foot-plates, providing for yielding movements thereof independently of each other in a direction away from the work-support, a trimming mechanism including cooperating shearing elements disposed above and normally clearing the foot-plates to trim said upturned marginal portions of material, and guard-blocks upon said foot-plates provided with shearing-element clearance recesses and having abutting surfaces crossing said presser-foot slot in position to divert the trimmed-off fabric-margins from the path of the needle.

5. In a sewing machine, in combination, a work-support, a presser-foot opposed to said work-support having spaced work-engaging portions providing a slot adapted to receive upturned marginal portions of material, a trimming mechanism including a ledger-blade and a movable blade arranged in cooperating shear-

ing relationship in position to trim said upturned marginal portions of material, ledger-blade supporting means, a diverter-blade extending across said presser-foot slot having its shank bent into circular form to embrace the ledger-blade supporting means whereby said diverter-blade may be swung into and out of operative position, and means for limiting the movement of the diverter-blade into operative position.

6. In a sewing machine, comprising, in combination, a frame including a fixed work-support and an overhanging bracket-arm, stitch-forming mechanism, work-feeding mechanism, a presser-foot opposed to the work-support having spaced work-engaging toes between which upturned marginal portions of material are adapted to pass, a trimming mechanism including a ledger-

blade and a movable blade arranged in cooperating shearing relationship in position to trim said upturned marginal portions of material, a primary trimming mechanism supporting bracket detachably secured upon said overhanging bracket-arm, supporting means for one of the trimmer-blades upon said primary bracket, an auxiliary bracket detachably secured upon said primary bracket, and supporting means for the other trimmer-blade upon said auxiliary bracket, whereby both trimmer-blade supporting mechanisms may be detached as a unit from the machine and one blade supporting mechanism may be detached from the machine independently of the other blade supporting mechanism. 80 85 90 95 96
